J. E. POWELL

GASOLINE CONSUMPTION TESTER

Filed July 28, 1925

Inventor

John E. Powell

UNITED STATES PATENT OFFICE.

JOHN E. POWELL, OF ISSAQAH, WASHINGTON.

GASOLINE-CONSUMPTION TESTER.

Application filed July 28, 1925. Serial No. 46,579.

My invention relates to accessories for automobiles, and consists of a device adapted to be installed in or connected with the gasoline supply mechanism so that when desired an accurate test may be made to determine the rate of gasoline consumption. My device is not of that character which will automatically give a continuous indication of the rate of consumption, but one which may be availed of whenever desired to indicate the rate of gasoline consumption at the time.

The object of my invention is, first, to satisfy the natural desire of drivers to know with what degree of efficiency the gasoline is being employed, by enabling the rate of gasoline consumption to be determined, to adjust the carburetor and as well the parts of the engine, and particularly to determine whether or not the piston and piston rings are operating effectively or wastefully. My invention consists essentially of a container which is inserted in the gasoline supply line between the carburetor and the source of supply of gasoline, which container is of a known capacity, and with this, means whereby the source of supply of gasoline to said container may be cut off when desired. In this way a supply of gasoline of known quantity can at any time be segregated from the main source of supply, and the main source of supply cut off, so that by observing the distance which the car will travel using this known volume of gasoline, the mileage secured per unit of measurement of gasoline, as a gallon, may be determined.

The invention consists of the novel constructions and combinations which will be hereinafter defined by the claims. The accompanying drawings show a simple and efficient means of constructing a device containing my invention.

Figure 1 is a side elevation of the engine of a car and the essential parts which are associated with my device.

Figure 2 is a sectional elevation taken through the container of my device.

It is evident that if a tank or container containing a definite and known quantity of gasoline be connected with the carburetor of a car, and means be employed whereby the engine can draw upon no other gasoline, the distance which the car will travel with this known and limited supply of gasoline may be used as a basis for determining the efficiency of action of the engine. It is the

purpose of my invention to supply a container of this character and means whereby this may be put into action whenever the above information is desired.

60

In the drawings, 1 represents an automobile engine, in side elevation; 2 represents a carburetor, which may be of any type of construction. In fact in such engines as may be operated without a carburetor, my device may be connected directly with the means employed for directly supplying the gasoline to the engine. While in accordance with the usual practice a carburetor would be employed and my device connected with the carburetor, it is to be understood that the carburetor is not strictly speaking an element of the combination which defines my invention.

70

In Figure 1 I have shown a suction tank 3, which is of standard construction such as is employed for supplying gasoline to the engine. This, however, may be considered as simply representing the source of supply of gasoline. Where supply tanks are used placed at such elevation that gravity feed to the carburetor may be relied upon, such tank forms the source of supply of gasoline. The device shown in Figure 2 is represented at 4 in Figure 1. This device consists of a container 4 of a known volume. This volume need not be large. In fact, for convenience in using my invention and determining the rate of consumption, I prefer that the capacity of this container and the pipes and chambers connected therewith when it is being used for this purpose, be a decimal fraction of a gallon, as, for instance, a tenth or a twentieth of a gallon. This particular size is preferred only because it makes the computations easier.

80

The gas is supplied to this container through the pipe 5, which is supplied with a cut-off valve 50.

100

The gasoline is delivered from this container to the carburetor through a pipe 6, which pipe, for convenience of accurate adjustment, may be extended upward above the bottom of the container 4. The pipe 6 is preferably secured in such a manner that it may be adjusted up or down. This may be easily secured by using a clamping device such as shown at 60, this being of a type of construction which is standard for connecting such small pipes as would be used for this purpose. This represents a construction in which the pipe 6 is not permanently fixed to any of the other

105

110

parts shown, but is held by the frictional grip thereon of the small conical ferrule 64 under pressure produced by screwing down the cap 60. Any other method of adjustably securing the pipe may be adopted. It is evident that by adjusting the level of the upper or intake end of the delivery pipe 6, the volume of the container 4, which would be drawn off by gravity, may be varied, and 10 in this way accuracy of volume may be obtained.

I may, and prefer to employ a screen as 61 within the container and extending over the upper end of the delivery pipe 6. This 15 screen, for convenience in placing its seat low, and yet providing vertical space for the adjustment of the pipe 6, would be made of conical shape, as has been illustrated. A removable cap 62 permits access to this container whenever desired. A vent pipe 63 extends upward from the container a sufficient distance to prevent any probability of gasoline being forced therefrom. The contents of this pipe, or at least that portion of 25 the pipe which may be filled with gasoline when the device is connected up for use, should be figured as a part of the contents of the container.

When a party having this device installed 30 upon a car desires to determine the mileage being then obtained from the gasoline, turns the valve 50 connecting the container 4 with the source of supply of gasoline, so as to cut off this flow. This should synchronize in 35 time with an observation of the speedometer reading, which reading should be noted. The car is then run until the gasoline contained in the container 4 has all been consumed and the car will run no farther. A 40 reading of the speedometer should at this time be made, and compared with the previous reading. If the volume of the container 4 and its connected parts is one tenth of a gallon, the reading of the speedometer 45 multiplied by ten, would give the mileage per gallon being obtained. If the volume

is one twentieth of a gallon, the reading must be multiplied by twenty. It is therefore possible, by the use of a device of small bulk, to quickly determine just what 50 rate of gasoline consumption is being obtained.

That portion of the container or bell 4 lying below the level of the upper end of the discharge tube 6 will function as a trap for 55 water and dirt found in more or less quantities in most gasoline. This can be drained off by disconnecting pipe 6.

What I claim as my invention is:

1. A gasoline consumption tester comprising a container having gasoline supply and gasoline discharge pipes independently connected therewith to include said container in the normal gasoline supply line, means for adjustably fixing the level of the inlet discharge pipe to vary the available volume of said container, and means for cutting off the gasoline supply to said container when desired. 60 65

2. A gasoline consumption tester comprising a container adapted for permanent connection in the gasoline supply line just ahead of the carburetor, a discharge pipe to the carburetor extending upwardly into the container means for adjustably fixing the 70 75 level of the pipe inlet to thereby accurately determine the available supply volume of the container.

3. A gasoline consumption tester comprising a container adapted for permanent 80 connection in the gasoline supply line just ahead of the carburetor, a discharge pipe to the carburetor extending upwardly into the container means for adjustably fixing the level of the pipe inlet to thereby accurately 85 determine the available supply volume of the container, and a vent pipe extending upwardly from said container to above the source of supply of gasoline.

Signed at Seattle, King County, Washington, this 20th day of July, 1925.

JOHN E. POWELL.
